Primary Examiner — Nathan M Johnston(74) *Attorney, Agent, or Firm* — Knobbe, Martens, Olson & Bear, LLP(57) **CLAIM**

The ornamental design for a wingnut for a flow alarm device, as shown and described.

DESCRIPTION

FIG. 1 is a perspective view of the wingnut for a flow alarm device;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is another perspective view thereof.

Broken lines are used to illustrate portions of the wingnut for a flow alarm device or environmental subject matter that form no part of the claimed design. The dot-dash-dot and/or the diagonal lines form the bounds of the claimed design and are not part of the claimed design.
